UNITED STATES PATENT OFFICE.

GEORGE H. BABCOCK, OF PLAINFIELD, NEW JERSEY.

DESIGN FOR A ROOFING-TILE.

SPECIFICATION forming part of **Design No. 19,888**, dated June 10, 1890.

Application filed May 14, 1890. Serial No. 351,814. Term of patent 14 years.

To all whom it may concern:

Be it known that I, GEORGE H. BABCOCK, a citizen of the United States, residing at Plainfield, in the county of Union and State 5 of New Jersey, have invented and produced a new and original Design for Roofing or Sheathing Tiles, of which the following is a specification, reference being had to the accompanying drawing, forming a part thereof.

10 My design relates to the architectural ornamentation of clay or other tiles by raised figures on the exposed faces thereof; and said design consists of a conventional plant-like figure having a series of vertical stems rising 15 from a base and terminating in divergent recurved leaves.

The drawing illustrates my design as applied to a tile having a semi-octagonal contour at its lower portion; but the said design 20 is applicable to various forms of tiles.

A represents the plane surface of the tile, above which the figure B is raised.

a is the base of the figure at or near the lower extremity of the tile, and *b* represents the raised stems, which are vertical and parallel, or nearly so, at their lower part, and which extend upward in divergent curves *c*, merging into the bulbulous leaves *d*, the majority of which are recurved, as at *e*, at their termination.

What I claim is—

The design herein shown and described for ornamenting roofing-tile, consisting in a raised figure on the surface thereof composed of a series of vertical stems projecting from 35 a base and expanding in diverging curves terminating in recurved leaves.

GEO. H. BABCOCK.
